Primary Examiner — Zenia Bennett(74) *Attorney, Agent, or Firm* — Muncy, Geissler, Olds & Lowe, PLLC(57) **CLAIM**

The ornamental design for a lamp holder, as shown and described.

DESCRIPTION

FIG. 1 is a perspective view of a lamp holder showing our new design;

FIG. 2 is a right side view of the lamp holder;

FIG. 3 is a rear view of the lamp holder;

FIG. 4 is a left side view of the lamp holder;

FIG. 5 is a front view of the lamp holder;

FIG. 6 is a top view of the lamp holder; and,

FIG. 7 is a bottom view of the lamp holder.

The broken lines in the drawing are for illustrative purposes only and form no part of the claimed design.

The lamp holder is shown broken away to show indeterminate length and for ease of illustration.
